(57) **CLAIM**

I claim the ornamental design for a training weight, as shown.

DESCRIPTION

FIG. 1—shows a perspective front, top and right side view illustrating my training weight design in use, the broken lines showing the operating environment only and forming no part of the design to be patented;

FIG. 2—shows a top and left side elevational view of my training weight design;

FIG. 3—shows a front elevational view of the design shown in FIG. 2;

FIG. 4—shows an elevational right side view of the design shown in FIG. 2;

FIG. 5—shows an elevational top view of the design shown in FIG. 2;

FIG. 6—shows a rear elevational view of the design shown in FIG. 2;

FIG. 7—shows and elevational left side view of the design shown in FIG. 2; and,

FIG. 8—shows a bottom elevational view of the design shown in FIG. 2.
